MANUFACTURE OF SLIP LASTED SHOES

Karl A. Stritter, Nahant, Mass., assignor to
United Shoe Machinery Corporation, Flemington, N. J., a corporation of New Jersey

Application November 27, 1946, Serial No. 712,602

5 Claims. (Cl. 36—16)

1

This invention relates to the manufacture of shoes and is herein illustrated in its application to the manufacture of stitchdown shoes by methods of shoemaking which do not require the use of a last or other form for shaping the upper for attachment to an insole.

It is an object of the present invention to adapt stitchdown shoes to slip lasting methods of shoemaking, so called.

In one aspect thereof the invention consists in a method of folding the margin of an upper on a defined fold line, herein illustrated as a row of stitches, attaching the folded margin of the upper to an extended sock lining by fastenings extending through the two thicknesses of the upper adjacent to the fold line and through the margin of the sock lining, the free margin of the upper being turned outwardly over said fastenings thereby concealing said fastening and the stitches which establish the fold line in the upper. The outturned margin of the upper is attached to a sole which may be a midsole or an outsole, depending upon whether the resulting shoe is a two-sole or three-sole construction. In the case of the three-sole construction the outturned margin of the upper may be attached to the midsole only in which case the outsole is cement attached to the midsole. In the manufacture of the three-sole construction the invention contemplates assembling the sock lining and midsole before positioning the upper on the sock lining and securing the folded margin of the upper to the sock lining by fastenings extending through the two thicknesses of the upper adjacent to the fold line and through both the sock lining and the midsole.

Invention is also to be recognized in the illustrated shoe construction comprising an upper the bottom margin of which is turned outwardly then inwardly over said outturned margin then outwardly again a sock lining the edge of which coincides with the extremity of the first-mentioned outturned portion, fastenings extending heightwise of the upper through the two lower layers of its marginal portion and through the margin of the sock lining, and a sole which may be a midsole or an outsole fastened to the marginal portion of the upper extending outwardly beyond the edge of the sock lining. Preferably and as herein illustrated, the marginal portion of the upper to which the sole is attached lies in a plane common to the sock lining. In vertical section the marginal portion of the upper lies adjacent to and conceals the outer fold in the margin of the upper and the edge of the sock lining.

These and other features and aspects of the

2

invention will now be described with reference to the accompanying drawings and pointed out in the appended claims.

In the drawings,

Fig. 1 is a plan view illustrating the toe portion of an upper embodying features of the present invention;

Fig. 2 is a cross sectional view showing a portion of an upper stitched to a portion of a sock lining;

Figs. 3 and 4 are cross sectional views illustrating alternative constructions embodying the upper and sock lining illustrated in Fig. 2;

Fig. 5 is a cross sectional view showing a modification of the construction illustrated in Fig. 2, the upper being stitched inside out to the sock lining; and

Fig. 6 is a cross sectional view showing the assembly illustrated in Fig. 5 turned right side out and completed by the attachment thereto of a mock welt and an outsole.

The drawings illustrate three alternative constructions. The manufacture of each of these constructions is characterized by the assembly of an upper and a sock lining off the last and the insertion of a last into the shoe so made. In two of the illustrated constructions the upper remains right side out in the course of the manufacture of the shoe while in the third the upper is turned inside out before attaching it to the sock lining and reversed before inserting the last.

In Fig. 1 there is illustrated a prefitted upper 10 having a line of stitches 12 uniformly spaced from the edge of the upper and arranged to establish a fold line. Referring to Fig. 2 the upper

is folded upon said line of stitches so as to bring the outer surface of the margin 14 into contact with the outer surface of the body portion of the upper. The upper is then mounted on an insole 40 or a sock lining 16 with its folded edge coinciding with the edge of the sock lining, and the upper and sock lining so assembled are attached together by fastenings or stitches 17 extending heightwise of the upper through the two thicknesses of the upper adjacent to the stitches 12 and through the margin of the sock lining. As illustrated in Fig. 3, the sock lining 16 has a marginal portion extending beyond the last bottom line upon which portion the outturned margin 50 of the upper is mounted. After attaching the upper to the sock lining a last 18 is forced into the shoe so made thereby to stretch and shape the upper and to facilitate the subsequent shoemaking operations. The free marginal portion

55 14 of the upper is then turned outwardly and

drawn downwardly into adjacent relation to the folded edge portion of the upper and the edge of the sock lining 16, and then turned outwardly, thus providing a sole attaching flange lying in the same plane as the sock lining. The shoe is completed by the attachment of a mock welt 20 and an outsole 22 to the outturned margin 14 of the upper by stitches 24.

In the manufacture of the shoe illustrated in Fig. 4 an upper which has its bottom margin folded, as shown in Fig. 2, is attached to an assembly comprising a sock lining 26 and a midsole 28 by fastenings or stitches 30. A mock welt 32 is then attached by stitches 34 to the outturned margin of the upper and the outwardly-extending margin of the midsole 28 and the shoe is completed by the cement attachment of an outsole 36 to the bottom of the midsole.

As shown in Fig. 5, an upper 38 having its bottom margin 40 folded over, as shown in Fig. 2, is turned inside out and attached in this position to the margin of a sock lining 42 of slightly less than last bottom area. The assembly so constructed is reversed or turned right side out and a last 44 (Fig. 6) is inserted into the shoe so made. The bottom margin 40 of the upper is then turned outwardly and a mock welt 46 and an outsole 48 are attached to said outturned margin by stitches 50. It will be seen that after the insertion of the last 44 the stitches 52 attaching the upper to the sock lining are arranged generally parallel to the plane of the last bottom.

Having thus described my invention, what I claim as new and desire to secure by Letters Patent of the United States is:

1. That method of making shoes which comprises folding the bottom marginal portion of an upper on a defined fold line, attaching the folded margin of the upper to a sock lining by fastenings extending through the two thicknesses of the upper adjacent to the fold line and through the margin of the sock lining, turning the free margin of the upper outwardly over said fastenings and over the fold line, thereby concealing both the fastenings and the fold line, and attaching said outturned margin of the upper to the margin of a sole.

2. That method of making shoes which comprises establishing a fold line in the bottom marginal portion of an upper, folding the upper upon said line so as to bring outer surfaces of the upper into contact with each other, mounting a sock lining upon a sole, attaching the folded margin of the upper to the assembled sock lining and sole by fastenings extending through the two thicknesses of the upper adjacent to the fold line, through the marginal portion of the sock lining

and through the sole, inserting a last into the shoe so made, turning the free margin of the upper outwardly, attaching said outturned margin and a welt to the margin of the sole, and cement attaching an outsole to said sole.

3. A stitchdown shoe comprising an upper the bottom margin of which is turned outwardly then inwardly then outwardly, a sock lining the edge of which coincides with the outermost fold in the upper, fastenings extending heightwise of the upper through the two lower thicknesses of the folded portion of the upper and through the margin of the sock lining, and a sole member fastened to the margin of the upper extending outwardly beyond the edge of the sock lining.

4. A stitchdown shoe comprising an upper the bottom margin of which extends outwardly then inwardly then outwardly again forming three layers in vertically superimposed relation, a sock lining the margin of which is extended so that its edge coincides with the edge of the outer fold of the upper, fastenings extending through the two lowermost thicknesses of the folded portion of the upper and through the margin of said sock lining, the bottom margin of the upper having a vertical section adjacent to the outer fold of the upper and the edge of the sock lining and a horizontal section extending outwardly in a plane common to the sock lining, and a sole member attached to said horizontal portion of the bottom margin of the upper.

5. A stitchdown shoe having an upper the bottom margin of which extends outwardly, then inwardly, then outwardly, and a sock lining, the edge of which coincides with the edge of the outer fold of said margin, said stitchdown shoe being characterized by an extension of said margin extending heightwise of the upper adjacent to the outer fold of said margin and the edge of the sock lining and extending outwardly along the surface of a sole, and a welt the inner edge face of which is arranged in contiguous relation to that portion of said margin extending heightwise of the shoe and the bottom face of which is arranged in contiguous relation to the outturned extremity of said margin.
